UNITED STATES PATENT OFFICE.

JOE C. WEBB, OF POND CREEK, OKLAHOMA.

CHICKEN-BROODER.

1,146,603.

Specification of Letters Patent. Patented July 13, 1915.

Application filed September 2, 1914. Serial No. 859,863.

To all whom it may concern:

Be it known that I, JOE C. WEBB, a citizen of the United States, residing at Pondcreek, in the county of Grant, State of Oklahoma, have invented certain new and useful Improvements in Chicken-Brooders; and I do hereby declare the following to be a full, clear, and exact description of the invention, such as will enable others skilled in the art to which it appertains to make and use the same.

This invention relates to chicken breeding apparatus, particularly to brooders for baby chicks, and has for its object the provision of a novel brooder provided with heating means whereby heat will be applied to the bottom of the brooder so that the feet of the chickens will be warmed quickly thus, as is a well known fact, warming the chickens to a comfortable degree in a very limited time.

An important object is the provision of a brooder having a hover suspended therewithin and spaced from the walls thereof, thereby avoiding crowding of the chickens against a wall with the consequence of smothering.

Another object is the provision of a brooder formed in compartments to provide a roosting chamber and an exercise room, the partitioning means being removable to facilitate cleaning the device.

Other objects and advantages such as simplicity and cheapness, efficiency and durability in service and the general improvement of the art will be brought out more fully in the following description and illustrated in the accompanying drawing, in which—

Figure 1 is a side elevation of my novel brooder, the ground beneath it being in section. Fig. 2 is a longitudinal vertical sectional view therethrough. Fig. 3 is a top plan view thereof with the cover removed. Fig. 4 is an end view. Fig. 5 is a bottom plan view, and Fig. 6 is a cross sectional view.

Referring more particularly to the drawing, the numeral 10 designates the main or body portion of my brooder as a whole, which comprises front and back walls 11 and 12, end walls 13 and 14, a bottom 15 and a cover 16 hingedly secured as at 17 upon the back wall 12. The rectangular closure formed by these walls is divided into two compartments 18 and 19 by means of a

partition 20 held between pairs of cleats 21 secured upon the front and back walls 11 and 12. It will be noted that the partition 20 may be removed for facilitating the cleaning of the device. The compartment 19 is adapted to be used as an exercising room in which the chickens may be fed and in which they may walk around to secure the proper exercise. Light is admitted to the exercising compartment through suitable windows 22 disposed in the front wall 11. In order to allow the chickens to pass into and out of the brooder, I provide an opening in the front wall 11 closable by a hinged door 23. Access may be had between the compartments 18 and 19 through an opening 24 formed in the partition 20. The end wall 14 of the brooder compartment is provided with an opening closed by a glazed door 24^a to allow access from the exterior of the brooder to the compartment 18.

A hover 25 is disposed within the compartment 18 and is formed preferably of a frame 26 supported upon cleats 27 and covered with a sheet of material 28 having a plurality of cloth strips 29 depending therefrom.

In order that heat may be applied to the brooder, I provide the floor 15 with a cutout portion 30 which is covered upon the top and bottom sides of the floor with sheets 31 and 32 of asbestos. When these plates are heated, heat will be supplied to the compartment 18 and at the same time danger of overheating will be prevented by virtue of the air space 32^a between the plates or sheets 31 and 32. The contact of the chickens' feet with the top sheet 31 will insure that they will be warmed while at the same time they cannot be burned as the upper sheet does not come in direct contact with the heating means.

In order to heat the plates 30 and 31, I provide a box 33 provided upon its upper side edges with flanges 34 slidable on tracks 35 secured upon the lower side of the plate 31. This box is adapted to contain any ordinary or preferred type of lamp which will heat the plates 30 and 31.

In use, a hole is first dug in the ground of a sufficient size and depth to more than accommodate the box 33. My brooder is then placed upon the ground with the box disposed within this hole 36, as shown in Figs. 1 and 6. The front portion of the hole is covered by a plate 37 hinged upon the front

wall 11 which excludes wind and consequently prevents the blowing out of the light in the lamp. When it is desired to extinguish the lamp or remove it from the 5 box for refilling or any other purpose the plate 37 is swung upwardly, whereupon the operator may reach into the hole 36 and grasping a handle 38 on the front of the box 33, pull the box forwardly upon the 10 track 35. It is to be observed that the tracks extend forwardly of the front wall 11 so that the box will still be supported thereby when it has been moved sufficiently far forwardly to permit of the removal of the lamp.

15 From the foregoing description and a study of the drawing it will be apparent that I have thus provided a simple and sanitary brooder comprising separate compartments for feeding and roosting, which may be 20 easily cleaned and which will effectively keep the chickens comfortably warm.

My brooder is constructed upon a logical plan in view of the fact that it provides for the warming of the chickens' feet which are 25 the part of a chicken the least protected and the quickest to get cold. It will thus be observed that I have provided a brooder which will fulfil all the functions that could be required of it.

It will be readily understood that I reserve the right to make various changes in the form and construction of parts without departing from the spirit of the invention or limiting the scope of the subjoined claims.

Having thus described my invention, I claim:

1. A brooder comprising a casing, the floor of the casing being provided with an opening, a hover disposed over said opening, sheets of asbestos secured on the floor above 40 and below said opening, and means for applying heat to the lowermost sheet, said means comprising a lamp.

2. A brooder comprising a casing provided with an opening in its bottom, sheets 45 of heat resisting material covering said opening and spaced apart, trackways secured upon the lower side of said bottom, a box provided at its upper edges with flanges slidable upon said trackways, and a lamp disposed within said box below said sheets of heat resisting material.

In testimony whereof I affix my signature, in the presence of two witnesses.

JOE C. WEBB.
